UNITED STATES PATENT OFFICE.

GEORGE W. STRAIGHT, OF CHICAGO, ILLINOIS.

TRUCK.

SPECIFICATION forming part of Letters Patent No. 637,044, dated November 14, 1899.

Application filed February 27, 1899. Serial No. 707,044. (No model.)

To all whom it may concern:

Be it known that I, GEORGE W. STRAIGHT, a citizen of the United States, and a resident of Chicago, in the county of Cook and State 5 of Illinois, have invented a new and useful Truck, of which the following is a specification.

This invention relates to trucks of the general type comprising longitudinal frame members secured together at a desired fixed distance from each other and truck-wheels revolvably mounted between said longitudinal frame members, and particularly designed and adapted for use in dry-kilns for lumber, 15 brick, and the like.

A primary object of my invention is to provide a truck of this type which will embody the features of great strength and rigidity with simplicity of construction and relative 20 cheapness of manufacture.

To this end the invention consists of the various features and combinations of features hereinafter shown and described.

In the accompanying drawings a truck of 25 my invention is fully illustrated.

Figure 1 is a side view of a truck of my invention. Fig. 2 is a top plan view thereof. Fig. 3 is an enlarged transverse vertical sectional view through the axle of one of the 30 truck-wheels, and Fig. 4 is an enlarged plan section on the line 4 4 of Fig. 2.

Referring now to the drawings, A designates the longitudinal frame members of my truck, consisting, preferably, of light steel 35 channel-bars. The longitudinal frame members A are rigidly secured together by riveting or bolting them to the flanges a of transverse frame members A', which consist, preferably, of sections of channel-bars of a length 40 substantially equal to the width of the longitudinal frame members A, disposed in such manner that the flanges a will extend transversely of said longitudinal members A. In the preferable construction shown, also, the 45 position of the extreme transverse frame members A' is such that the plane surfaces a' of

the webs thereof will be flush with or will project slightly beyond the ends of said longitudinal frame members A. They will thus form buffers and will receive the impact 50 caused by one car running into another and will operate to distribute the force of the blow to both of the longitudinal members, thus preventing all tendency of said members A to shift under said blow.

The truck-wheels A² are preferably provided with antifriction-bearings and are mounted upon axles A³, secured against rotation in the longitudinal frame members A. In the preferable construction shown the 60 axles A³ are provided with reduced ends a², which are made slightly tapering, being smallest at their outer ends. The reduced taper ends a² are forced into alined holes formed in the longitudinal frame members A, thus securing said axles against rotation in the desired manner.

I claim—

A truck comprising longitudinal frame members, consisting of channel-bars disposed 70 with their plane faces toward each other, transverse frame members, consisting of sections of channel-bars, the longitudinal frame members being riveted, or otherwise rigidly secured to the flanges of said transverse 75 frame members and the extreme transverse frame members being disposed with their plane faces flush with the ends of the longitudinal frame members, and truck-wheels revolvably mounted on axles between said longitudinal frame members, the ends of said 80 axles being tapered and being secured by frictional engagement in holes formed in the longitudinal frame members, substantially as described.

In testimony that I claim the foregoing as my invention I have hereunto set my hand this 25th day of February, 1899.

GEORGE W. STRAIGHT.
